UNITED STATES PATENT OFFICE.

JAMES MACPHAIL, OF DAVENPORT, IOWA, ASSIGNOR TO DAIN MANUFACTURING COMPANY OF IOWA, OF OTTUMWA, IOWA, A CORPORATION OF IOWA.

TOOTH-HOLDER FOR SULKY HAY-RAKES.

1,099,150.

Specification of Letters Patent.

Patented June 2, 1914.

Application filed July 9, 1913. Serial No. 778,017.

To all whom it may concern:

Be it known that I, JAMES MACPHAIL, a citizen of the United States, residing at Davenport, in the county of Scott and State of Iowa, have invented certain new and useful Improvements in Tooth-Holders for Sulky Hay-Rakes, of which the following is a specification, reference being had to the accompanying drawings.

10 This invention relates to improvements in the means for holding in place on a rake the heavy wire teeth of the rake.

It has for its objects to so form or shape the holder that it can be pressed from a single 15 sheet of steel and will be light in weight and very strong; that will securely hold the teeth in place without liability of side play and yet will so hold the "lateral" or turned upper end of each tooth bar as to 20 permit the desired flexing or oscillating of the tooth in its openings in the holder and at the same time provide an extended and rigid bearing for such turned end. I accomplish these objects by the construction 25 shown in the drawings and hereinafter particularly described.

That which I believe to be new will be set forth in the claims.

In the drawings, Figure 1 is a face view 30 of one of the improved holders applied in position on a rake, and showing also the upper parts of a number of rake teeth held by said holder; Fig. 2 is an enlarged vertical section through the parts shown in Fig. 1; 35 Figs. 3 and 4 are views similar to Figs. 1 and 2, respectively, but showing a modification in the form of the holder; Fig. 5 is a perspective view of the holder of Fig. 1, looking toward the under face thereof; and 40 Fig. 6 is a similar view of the form of holder shown in Fig. 2.

In the several figures in which corresponding parts are indicated by like reference characters, 10 indicates a rake head 45 extending from side to side of a sulky hay-rake, and, as shown, formed of a piece of angle-iron.

11 indicates a number of rake-teeth of heavy spring wire which are held in place 50 on the head 10 by my improved holding means. Each tooth is turned at right angles to form what is known in the trade as a "lateral," such portion being here indicated by 12.

55 The parts so far named are common to

Figs. 1 and 4, but referring now particularly to Figs. 1, 2 and 4, the tooth-holder as a whole is indicated by 13. It is best formed of a pressed steel plate as thereby the maximum strength combined with the minimum 60 of weight is secured. The holder at its lower portion is made channel-shaped, the lower flange of such channel portion being indicated by 14, the back thereof by 15, and the upper flange by 16. The lower flange, in 65 the construction shown, is substantially horizontal while the upper one is slightly inclined upward. 17 indicates an extension of the upper flange, which extension, as shown, is formed by bending the sheet of 70 material backward and then upward, such bending being such as to produce substantially an ogee curve. Such extension 17 provides, as will hereinafter appear, a suitable support for the turned ends or "lateral- 75 ers" of the rake-teeth to rest upon, and, in connection with the two walls of the angle-iron 10, forms a housing or inclosure for such "laterals." 18 indicates a series of notches in the lower flange 14, and 19 indicates a series of holes each formed in the parts 16 and 17, the holes 19 being alined 80 with the notches 18. 20 indicates bolt holes through the wall 15 of the channel through which pass bolts 21 for securing the holders 85 to the angle-iron head 10.

For convenience in connecting and disconnecting the teeth the holder is made up of several sections or pieces placed end to end, and one only of such sections or pieces 90 13 is shown. Each of such sections is adapted to secure in place a plurality of teeth and as such number of teeth varies according to the wishes or ideas of different users each section is preferably constructed with more 95 notches 18 and holes 19 than are in use for teeth at any one time, and thereby by a proper selection of such notches and holes the user of the rake can space the teeth at the desired distance apart. To put into use 100 the holder, formed of a plurality of the sections 13 placed end to end, the teeth are placed so that they extend through the desired alined notches 18 and holes 19 and have their turned upper ends or "laterals" resting upon the curved upper surface of the extension 17. The holder is then placed against the inner face of the vertical wall of the angle-iron head 10 and bolted in place 105 by the bolts 21. When thus in place it will 110

be seen that the curved member 17 and the two walls of the angle-iron head 10 constitute the walls of a chamber in which snugly fit the "laterals" 12 of the several rake-teeth, the said "laterals" being thus prevented from rattling or wabbling, but being free to have a slight turning or hinge-like movement when the teeth spring as the result of meeting with an obstruction. Such movement of the teeth due to their being compelled to yield from time to time on account of meeting obstructions is not interfered with by the holder, but such necessary movement is permitted by the character of the pair of openings in the holder through which each tooth passes, such openings, while acting to prevent any material side movement of the tooth not acting to prevent the slight amount of movement caused by the springing of the tooth when it meets an obstruction. Each hole 19 being formed through the members 16 and 17 and such parts standing at an angle to each other such holes constitute in effect merely retaining notches as are the notches 18 located below them, but by reason of the holes being formed through both members 16 and 17 the notches thus formed present double the amount of side bearing for the teeth than do the notches 18. With three bearing points at each side of each tooth and with the "laterals" at the upper ends inclosed as shown and described, it will be understood that the teeth will be maintained at all times in proper working position. The bending of the metal sheet as shown to form the parts 16 and 17 is of very considerable advantage in another way also, for by so bending it and presenting the bend to and against the angle-iron 10 a very stiff construction of holder is provided whereby buckling or distortion of the holders is prevented in case the nuts on the securing bolts 21 are screwed up very tight.

Turning now to the modification in the construction of the holder shown in Figs. 3, 4 and 6,—22 indicates the holder as a whole, which, as in the first-described construction I form from a single piece of metal. In this holder the back wall thereof is indicated by 23 and is provided with a flange 24 at its lower edge, in which edge is formed tooth-retaining notches 25. The upper portion of the wall 23 is slit to permit of the bending down of pieces that form brackets 26 that are substantially parallel with the flange 24 and are adapted to support the rake-teeth "laterals" when the holder is bolted in place, as best shown in Fig. 4. The spaces between the brackets 24 are in alinement with the notches 25 and, together with such notches 25, act to hold the teeth in working position. 27 indicates bolt-holes for the passage of the retaining bolts 21 by which the device is fastened to

the angle-iron head 10. When so fastened in place it will be seen that the rake-teeth "laterals" are inclosed or housed by the two walls of the angle-iron 10 and by the brackets 26 and those extensions of the wall 23 that are between and rise above such brackets. The same secure retention of the "laterals" is had in the angle of the head 10 as in the first-described construction and the same slight hinge-like action permitted when the rake-teeth are sprung by meeting an obstruction. The formation of the separated and inturned brackets 26 produces in effect a holder of channel-like construction, of which such brackets constitute one of the flanges, so that in this respect the two constructions resemble each other, and they also are alike in that each provides, when attached in place to an angle-iron head, as shown, an inclosed chamber above the channel portion, in which chamber the rake-teeth "laterals" are housed and permitted to rock as required.

That which I claim as my invention, and desire to secure by Letters Patent, is,—

1. The combination with an angle-iron rake-head, of a tooth-holder secured to the inner face of one wall of said angle-iron, said holder comprising a channel portion that bears against a wall of the angle-iron and having an extension that forms a wall of a housing adapted to receive a rake-tooth lateral, the walls of said angle-iron constituting a portion of said housing.

2. The combination with an angle-iron rake-head, of a tooth-holder secured to the inner face of one wall of said angle-iron, said holder comprising a channel portion that bears against a wall of the angle-iron and having an extension that forms a wall of a housing adapted to receive a rake-tooth lateral, the walls of said angle-iron constituting a portion of said housing, the flanges of said channel portion having alined openings to receive the rake-tooth.

3. The combination with an angle-iron rake-head, of a tooth-holder secured to the inner face of one wall of said angle-iron, said holder comprising a channel portion that bears against a wall of the angle-iron, said holder having means for confining a rake-tooth lateral above said channel portion and in the angle of said angle-iron.

4. The combination with an angle-iron rake-head, of a tooth-holder formed from a single sheet of metal and comprising a channel portion that bears against one wall of the angle-iron, the upper flange of said channel portion being provided with a rearward and upward extension that, in connection with the walls of the angle-iron, forms a housing or chamber for the reception of a rake-tooth lateral.

5. The combination with an angle-iron rake-head, of a tooth-holder formed from a

single sheet of metal and comprising a channel portion that bears against one wall of the angle-iron, the upper flange of said channel portion being provided with a rearward 5 and upward extension that, in connection with the walls of the angle-iron, forms a housing or chamber for the reception of a

rake-tooth lateral, said upper flange and the said extension having a hole therethrough to form a tooth-holding notch.

JAMES MACPHAIL.
